UNITED STATES PATENT OFFICE.

JOHN SCHNEIDER, JR., OF NEW YORK, N. Y., ASSIGNOR TO ALBERT HOCHISTER, OF SAME PLACE.

DESIGN FOR A FRAME FOR TOY TROLLEY-CARS.

SPECIFICATION forming part of Design No. 30,494, dated April 4, 1899.

Application filed March 10, 1899. Serial No. 708,602. Term of patent 14 years.

To all whom it may concern:

Be it known that I, JOHN SCHNEIDER, Jr., a citizen of the United States, and a resident of the borough of Queens, Queens county, in the city of New York and State of New York, have invented a certain new, useful, and original Design for Frames of Toy Trolley-Cars, of which the following is a specification, reference being had to the accompanying drawings, which form part thereof.

The invention relates to a design for frames of toy trolley-cars; and it consists of the novel configuration and shape herein shown and claimed.

In the accompanying drawings, Figure 1 is a side elevation of such a frame embodying my new design. Fig. 2 is a plan view, and Fig. 3 is a perspective view of the same.

The characteristic features of my design consist in the configuration and shape of the frame shown, comprising a flat platform composed of side bars 1 1 and end platforms 2 2 and having at each end thereof upturned end

dashboards 3 3 and at about the middle thereof, at each side, upturned projections 4 and 5, respectively, one of which, 4, has end wings and is larger than the other. In proximity to the end platforms 2 2 are downwardly-extending pedestals 6 and 7 on one side and 8 and 9 on the other side of the frame, the pedestal 6 being nearer the end of the frame than the opposite pedestal 8 and the pedestal 7 being nearer the end of the frame than the opposite pedestal 9.

What I claim, and desire to secure by Letters Patent, is—

The design for a frame of a toy trolley-car, substantially as shown and described.

Signed at the borough of Manhattan, county of New York, city of New York, and State of New York, this 9th day of March, 1899.

JOHN SCHNEIDER, JR.
